UNITED STATES PATENT OFFICE.

WILLIAM CLARENCE PICKELL, OF HIGHLAND PARK, MICHIGAN.

PAPER-SHEET HOLDER.

Application filed December 8, 1924. Serial No. 754,634.

My invention relates to improvements in paper holders which have clamps with thin convex heads, said heads are made to press down upon and hold the corners or edges 5 of a sheet of paper flat against a board. The stems of the clamps are held by nuts and springs within cylindrical shaped housings, said housings being inserted a press fit in holes in the board. The tops of the housings 10 being even with the top of the board. The heads of the clamps when moved by the fingers slide around in a circle and over inclined cams which are upon the tops of the housings, and drop off the ends of said 15 cams upon the corners of the sheet of paper. The clamps have sharp edges on the ends which by the aid of the springs pinch the corners tight enough to hold the sheet in place while drawing and when said drawing 20 is complete said sheet may be released by sliding the heads of said clamps around and off the corners.

The objects of my improvements are:

First, to provide a quick and easy releas- 25 ing paper holder for standard drawing sheets such as are now used in public schools, colleges, universities, technical schools and certain drafting rooms.

Second, to provide a clamp for holding 30 drawing paper and sketch paper in place while drawing and said clamp to remain in position inserted in a drawing board for as many drawings as desired without removing said clamp.

Third, to provide a suitable device to take 35 the place of the common thumb tack, one which will not have to be pressed in and taken out for each drawing.

Fourth, to provide a suitable device for 40 clamping each corner of a standard sheet of paper in the same place on a flat smooth surface and quickly releasing each corner when work on the sheet is complete.

I attain these objects by the mechanism, 45 illustrated in the accompanying drawing in which:—

Fig. 1 is a plan view showing the top of the holder inserted in a piece of board and the circular movement of the head when putting on and taking off the corner of a sheet 50 of paper.

Fig. 2 shows a section of the holder inserted within a piece of board, the top of the housing coming flush with the top surface of the board and the clamp head resting on 55 said top surface of the board.

Fig. 3 shows a bottom view of the holder inserted within a piece of board and the parts which are exposed.

Fig. 4 shows a top view of four holders 60 inserted within a drawing board and each holder clamping down a corner of a drawing sheet.

Fig. 5 shows a top view of the cylindrical 65 housing.

Fig. 6 shows a section of the cylindrical housing taken at 1—1 illustrating the formation of the pressed metal shape.

Fig. 7 shows the clamping pin, a section 70 of a ball-bearing and two lock nuts.

Fig. 8 shows the bottom view of the clamping pin and lock nuts.

Similar numerals refer to similar parts throughout the several views.

The hollow cylindrical housing 1 is inserted 75 a press fit into a hole 22 bored in or through the drawing-board 2 and made to come flush with its top surface, with the cam portion of said housing protruding above said board as shown at 1 in section 80 of Fig. 2. The clamp 3 has a threaded stem 4 which is a slip fit in the hole 5 of the housing 1. Within the cylindrical housing 1 a ball-bearing 6—7—8 is made a slip fit over the stem 4 which helps clamp 3 to 85 revolve easily around the circle 20 shown in Fig. 1. This ball-bearing 6—7—8 is pressed up against the inner part of the housing 1 by a short spring 9. When the lock nuts 10—11 are adjusted tight enough on the stem 90 90

4 they press the spring 9 against the ball-bearing 6—7—8 and force the sharp edge 12 of the clamp 3 against the sheet of paper 13 on the board 2. When taking the sheet 95

of paper 13 off the board 2 the clamp 3 is forced to revolve by the finger pressed against its edge until it comes to the position 14 as shown in Fig. 1. When placing the sheet of paper under the clamp 3 the 100 corner of said sheet is placed in position as shown at 15 in Fig. 1 and clamp 3 is forced in the direction indicated by the arrows 16 over the cam 17 until said clamp 3 drops off the edge 18. The spring 9 is adjusted tight 105

enough to force the sharp edge 12 against the paper 13 so that it remains in position until the required drawing is complete. The cam 17 is a pressed inclined ridge in the sheet metal housing 1, and starts even with the top at 19 of said housing and circles around hole 5, and slopes upward to the end 18. The clamp 3 when moved around by the 110

finger drops off the end 18 and down upon the corner of the sheet of paper as shown in Fig. 1. Said cam 17 may be made to swing around hole 5 in either direction by 5 making the incline either right hand or left hand as desired. Flange 21 and nut 23 will prevent the housing 1 from coming loose in the hole 22.

Having described my invention, what I 10 claim as new and desire to secure by Letters Patent is:

1. A paper holder for drawing boards comprising a cylindrical housing open at one end and partially closed at the other 15 and being of a length sufficient to extend through the thickness of the board in connection with which it is to be used, a cam on the partially closed end of said cylinder, an L-shaped lever extending through said cylinder and having one end thereof arranged to ride over said cam, a spring in said cylinder and surrounding one end of said lever for holding said lever in its lowermost position, and means for retaining said 25 spring in operative position.

2. A paper holder for fastening paper to a drawing-board, comprising a cylindrical housing open at one end and partially closed at the other, with a flange on said partially 30 closed end, an inclined cam on top of said housing made to curve a part of the way around the hole on top of the partially closed end, an L-shaped clamp extending through said hole, having one end bent to 35 extend over the top of said cylindrical housing, the other end having a coil spring around the shaft portion which extends within said cylindrical housing and means for retaining said shaft and spring within 40 said housing and in operative position.

3. A paper holder for drawing boards comprising a cylindrical housing open at one end and partially closed at the other, with a flange around the partially closed 45 end thereby keeping the top of said housing flush with the top of said drawing board for which it is to be used, and said housing containing an L-shaped clamp with a flattened end bent at right angles to a round 50 stem, said stem being inserted through a hole in the partially closed end of said housing, around said stem and within said housing a spring being coiled and held on said stem by two nuts said nuts being 55 adapted to hold said stem, to vary the ten-

sion on said spring and the grip on said clamp, a cam on the top of the partially closed end of said housing means for raising said clamp sufficiently high enough above the surface of said drawing board and the top of said housing to clear the paper for which it is adapted to clamp. 60

4. A paper holder for drawing boards comprising a cylindrical housing open at the bottom and partially closed at the top, 65 an incline cam on the top of said cylindrical housing and which curves around the hole in said top, said housing containing an L-shaped clamp with one end bent at right angles to the stem which is made to fit into 70 the hole in the top of said cylindrical housing, within said housing and over said stem there being a spring which is held in place by a nut forming means for keeping a pressure on the bent portion of said clamp head 75 and pinch the corner of the drawing paper which it is intended to clamp and hold.

5. A paper holder for drawing boards comprising a housing adapted to be mounted in a drawing board, a reciprocable 80 and rotatable member in said housing provided with an overhanging paper engaging end, means in said housing adapted for holding said member in a retracted paper engaging position, and means adjacent the 85 overhanging paper engaging end of said member upon which said member is adapted to be turned to raise it out of engagement with the paper.

6. A paper holder as called for in claim 90 5, wherein the last mentioned means is carried by said housing and has the configuration of an arcuated cam.

7. The combination with a drawing board 95 upon which paper is adapted to be mounted, of a housing mounted in the drawing board with its inner end substantially flush with the lower face of the drawing board, a reciprocatable and rotatable spring held 100 paper engaging member supported from said housing and adapted to exert pressure on a sheet of paper adjacent said housing for holding the paper on said board, and means in the arcuate path of said member 105 adapted for raising said member when rotated to release the sheet of paper relative to said board.

In testimony whereof I have hereunto set my hand this 2nd day of December, 1924.

WILLIAM CLARENCE PICKELL.
